UNITED STATES PATENT OFFICE

REGINALD BOYD WOODCOCK AND JOSHUA COOK, OF LEICESTER, ENGLAND, ASSIGNEES
TO UNITED SHOE MACHINERY CORPORATION, OF PATERSON, NEW JERSEY, A COR-
PORATION OF NEW JERSEY

SKIVING MACHINE

Application filed April 11, 1927, Serial No. 182,929, and in Great Britain April 17, 1926.

This invention relates to skiving machines and is herein illustrated as embodied in a machine having a cylindrical skiving knife and adapted more particularly to skiving the 5 margins of pieces of sheet material such as leather which are to be used in the manufacture of boots and shoes.

In such machines the knife is commonly mounted to rotate about a horizontal axis, the 10 work being fed to the machine by a feed roll located partly within the knife and closely adjacent to the upper portion of the edge thereof, the work being held down upon the feed roll by a presser (which may be a driven 15 roll) located above the feed roll. The work passes between the feed roll and the presser and thence over the knife while the skivings pass into the interior of the knife and are directed by a suitable guide out of the knife 20 to the top of the bench upon which the machine is mounted.

Features of the invention, as herein illustrated in their application to machines of the type referred to, relate to improved means 25 for adjusting the knife, an improved mounting for the feed roll, an improved change-speed gearing for driving said roll and an improved mechanism for driving the knife grinder.

30 These and other features of the invention will be described as embodied in an illustrated machine and pointed out in the appended claims.

Referring now to the accompanying drawings,

Fig. 1 is an end elevation of the illustrative machine;

Fig. 2 is a plan view of the illustrative machine;

Fig. 3 is a front elevation of the illustrative machine;

Fig. 4 is a plan view, on an enlarged scale, of the illustrative machine partly in section 45 and with some of the parts in section;

Fig. 5 is a front elevation, on the same scale as Fig. 4, of the left-hand end of the machine with some of the parts in section;

Fig. 6 is a front sectional elevation of the 50 right-hand end of the machine;

Fig. 7 is an elevation of the machine partly in section; and

Fig. 8 is a section on the line VIII—VIII of Fig. 4, viewed as indicated by the arrows. Before proceeding to a detailed description of the illustrated skiving machine, in which description the terms front, rear, right-hand end and left-hand end will be used, it should be understood that the front of the machine is exposed to view in Fig. 3. The operator of the machine occupies the position of the observer of that figure and presents the work to the machine from left to right, as indicated by the arrow. In the illustrated machine the cylindrical knife 1 (Fig. 5) is made of a single piece of metal and is fixed by four screws 2 to a flange 3 formed on the end of a horizontal sleeve 4. The sleeve 4 is rotatably mounted in a bushing 5 which is 60 slidable axially in a bearing 6 within a hollow machine frame 7. The end of the bushing 5 adjacent to the knife is enlarged, where it projects beyond its bearing 6, and has formed in it a recess which receives a ball-bearing 8 positioned between the bottom of 65 the recess and the flange 3 on the sleeve 4 to take the thrust on the knife edge. The sleeve 4 at its right-hand end (Fig. 4) has threaded on it a collar 9 which is adjusted and clamped in position so as to prevent endwise movement of the sleeve in the bushing 5. The bushing 5 has formed on it near its right-hand end rack teeth 10 (Fig. 4) which mesh with a gear segment 11 formed on the 70 end of a horizontal arm 12 of a bell-crank 75 lever pivoted on a vertical stud 13 fixed in the frame. The part of the stud on which is pivoted the bell-crank lever is eccentric to that part of the stud which is fixed in the frame so that by rotating the stud the gear teeth 11 on the segment may be caused 80 to mesh properly with the rack teeth 10 on the bushing 5. The other arm 14 of the bell-crank lever is forked and has rotatably 85 mounted in it a pin 15 through which is threaded a screw 16 passing through the fork. The screw 16 is rotatably mounted in a pin 17 which is rotatably mounted in the frame 7; and the screw has on it a collar 18 which engages one side of the pin 17 and has fixed to it 90 95

a hand-wheel 19, which engages the other side of the pin so as to prevent endwise movement of the screw through the pin. When the screw 16 is rotated, the bell-crank lever 12-14 is swung about its pivot 13, and, through the gear segment 11 and rack 10, the bushing 5 and with it the knife 1 are adjusted axially. When the bushing and knife have been adjusted the bushing is locked in position by a horizontal hand-screw 20. Extending upwardly from the enlarged end of the bushing 5 (Fig. 5) is a pin 22 which enters a hole in a plate 23 slidingly mounted in a guideway formed on the upper face of the frame 7. The plate 23 at its left-hand end is shaped to fit closely up to the rear of the knife 1 and as the knife is adjusted axially, the plate 23 moves with it and prevents a gap from being left between the back of the knife and the frame where the knife projects up through the frame. The bore of the sleeve 4 has formed in it two opposed axial grooves 24, 24 which receive tongues 25, 25, formed on a driving shaft 26 coaxial with the sleeve, so as to provide a driving connection between the shaft and sleeve while allowing axial adjustment of the sleeve. The driving shaft 26 is rotatably mounted in a bearing formed in the frame of the machine and has on its end fast and loose pulleys 27, 28 (Fig. 6) for a driving belt.

A combined belt shifter and belt guard is provided and comprises a ring 29 surrounding the driving shaft and fixed to two spindles 30, 31 slidingly mounted in the frame parallel to the driving shaft, the ring 29 and collars 32 limiting the sliding movement by engagement with the frame. Clamped to the ring concentric to the driving shaft is a substantially cylindrical casing 34 surrounding at least one of the pulleys and having in it openings 35 (Fig. 3) through which the belt enters and leaves as it passes around the selected pulley. The member 34 has projecting from it a handle 36 by which it may be moved from one pulley to the other to shift the belt. The slots in the ring 29 permit of the member 34 being rotated about the shaft axis to position the belt openings according to the direction in which the belt approaches the pulleys.

The driving shaft 26 (Fig. 8) has formed on it a spiral gear 37 which meshes with a spiral gear 38 fixed on a counter-shaft 39 extending toward the rear of the machine. The counter-shaft 39 has fixed to it at its rear end a spiral gear 40 which meshes with a spiral gear 41 fixed on a feed shaft 42 which, as will be explained, drives the feed roll and the knife grinder. The shaft 39 is rotatably mounted in bearings in a casing 43 which encloses the spiral gears and contains oil in which the gears run. The casing 43

is mounted on the bearings of the driving and feed shafts.

The feed roll 77 (Fig. 4) is mounted, in a manner presently to be described, in a cover 50 which is pivoted to the frame about the vertical pivot 100, so that the cover, and with it the feed roll, may be swung outwardly when desired to give access to the knife, said feed roll being driven, as has been stated, from the shaft 42. This shaft, at its left-hand end is rotatably mounted in a grinding wheel driving sleeve 146 which is in turn rotatable in a sleeve 44 carried by the frame of the machine. The shaft 42 has fast to it a toothed clutch member 45 which cooperates with a second toothed clutch member 46. The latter clutch member is formed on a spindle 47 in axial alinement with the feed shaft 42 and slidingly keyed in the bore of a feed roll driving member 48. The driving member 48 is rotatably mounted in a bushing 49 fixed in the swinging end cover 50 of the frame 7. The spindle 47 is bored to receive a spring 51 bearing against the end of the bore in the spindle and against the end of the bore in the driving member 48. The spring 51 permits the clutch member 46 to yield if, when the clutch members are brought together by the closing of the swing cover 50, the clutch teeth are opposite one another; and, as the feed shaft 42 rotates, moves the members into clutching engagement. The bushing 49 has screwed on its left-hand end where it projects through the cover 50 a cap 52 and that end of the driving member 48 has in it a recess which receives a hardened block 53 and a ball 54 the latter bearing against the cap to take end thrust imparted to the driving member by the spring 51. When the swing cover is open, outward movement of the clutch member 46 by the spring 51 is limited by a stop collar 55 fixed in the swing cover.

The driving member 48 has formed on it a spiral gear 56 which meshes with a spiral gear above the driving member and fixed on a shaft 57. The shaft 57 is rotatably mounted in bearings in the swing cover 50 and has slidingly keyed on it a pair of spur gears 58, 59 of different diameter which may be moved along the shaft 57 to bring one or other of the gears into mesh with one or other of a second pair of gears 60, 61. The first pair of gears 58, 59 are moved along their shaft by a hand lever 62 pivoted on a vertical stud 63 fixed in the swing cover 50. The hand lever 62 has pivotally mounted in one end of it a block 64 which is shaped to straddle the shaft and engage between the pairs of gears 58, 59. The lever at its other end is provided with a hand-hold and carries a spring plunger 65 having a V-shaped outer end adapted to snap over to one side or other of a V-shaped block 66 fixed in the swing cover 50 to hold the gears in mesh. By this means a two-speed drive is provided for the feed mechanism.

The gears are arranged in a chamber 67, formed in the swing cover 50, adapted to hold a supply of oil for the gears, and closed by a suitable cover plate 68.

5 The shaft 69 (Fig. 7) on which the second pair of gears 60, 61 is mounted has an enlarged end 70. This end 70 is bored and slotted axially to receive the ball end 71 of a rod 72 and pin 73 extending through the ball so as to provide a universal joint. A 10 spring plunger 74 in the shaft 69 engages the ball 71 and urges it toward the outer end of the shaft. The rod 72 has at its other end a second ball 75 having a pin 76 passing 15 transversely through it, which ball end makes universal driving connection with the lower feed roll 77, said roll being substantially barrel-shaped, the curvature of its periphery lengthwise of the roll being substantially the same as the curvature of the knife edge. The 20 lower feed roll 77 is keyed on a sleeve 78 which is rotatably mounted at one end in a horizontal stud 79, said stud being fixed in a roll-carrying member 80. The sleeve 78 at its other end is bored and slotted to make 25 universal connection with the forward end of the ball-rod 72, and this end of the sleeve is threaded to receive a collar which holds the roll 77 in place. The roll-carrying member 80 has extending from it (Fig. 4) a stud 30 81 which is rotatably mounted in a swinging frame 82 rotatably mounted on a rod 83 fixed in the swing cover 50. The axis of the stud 81 passes some three-eighths of an inch above the 35 axis of the rod 83 and at right angles thereto, and the roll-carrying member 80 and the swinging frame 82 and their pivots 81, 83 are arranged as close as possible to the top of the swing cover 50. By this means the lower 40 feed roll 77 can swing downwardly about the axis of the rod 83 for different thicknesses of work and can tip endwise about the axis of the stud 81 for different inclinations of bevel. The stud 81 has fixed to it a depending arm 84 45 (Figs. 4 and 5) within the swing cover, and this arm has attached to it one end of a spring 85 tending to urge the roll upwardly about the axis of the stud 81. The other end of the spring is fastened to a screw 86 fixed in a rod 87 projecting through a horizontal slot 50 extending rearwardly of the machine and formed in the swing cover 50. The rod 87 has fixed in it by the screw 86 a vertical pin 88 which engages a face on the inside 55 of the swing cover and has a rectangular flange 89 which engages a face on the outside of the cover. The rod also has on its outer end a handle 90 by which the rod 87 may be moved along the slot to adjust the 60 tension of the spring 85, said rod being locked by the pull of the spring which binds the pin 88 and flange 89 against the cover. Upward movement of the roll 77 under the influence of the spring 85 is limited by a screw 65 91 threaded into the roll-carrying member

80 and engaging the under side of the cover 50. The swinging frame 82 has a depending arm 92 (Fig. 5) inside the swing cover 50. A spring plunger 93 carried in the swing cover 50 engages the arm 92 to urge the lower feed roll 77 upwardly about the axis of the shaft 83. A hand-screw 94 by which the tension of the spring of the spring plunger may be adjusted is arranged on the outside of and at the left-hand end of the swing cover. Upward movement of the swinging frame is limited by an adjustable screw 95 in the swinging frame 82 which engages the under side of the top of the swing cover 50.

70 An edge gage (not shown) is fixed on the top face of the swing cover 50. The swing cover 50 is hollow and is substantially rectangular in shape having an open side and an open bottom and is pivoted, as has been explained, on a vertical shaft 100 fixed at the rear of the frame 7 and substantially in line with the edge of the open side of the cover. When the cover is closed, the open side fits up against the left-hand end of the frame, and the joint between the two extends rearwardly substantially in the same plane as the axis of the lower feed roll 77.

75 The front, rear and left-hand walls of the cover are cut away (Figs. 3 and 1) to provide an opening through which the waste skivings may freely pass. The lower edges of the front and rear walls are some inch and a quarter above the lowest point of the knife; and the lower edge of the left-hand wall at its middle portion is some two inches above 80 the lowest point of the knife. With this construction, the waste skivings may pass freely out upon the bench upon which the machine rests; and if, by chance, they fail so to pass out and become clogged inside the cover, the 85 operator may readily insert a small rod or other suitable tool and clear them away. A plate of suitable shape (not shown) may be fixed inside the cover to direct the skivings 90 downwardly away from the lower feed roll mechanism.

95 The cover has pivotally connected to its front wall on a vertical pin 101 (Fig. 3) a rod 102 having its outer end threaded to receive a hand-nut 103 by which the cover 100 may be closed or opened. When the cover is closed, the rod is swung between arms 104 (Fig. 2) of a fork projecting from the frame 7, and the nut is screwed up against the outer face of the fork to lock the cover 105 in closed position. The pin 101 has fixed on it within the cover a cam 105 (Fig. 5) which, when the rod is swung away from the fork 110 to allow the cover to be opened, engages an arm 106 depending from the lower feed roll swinging frame 82 and depresses the feed roll 77, before the cover can be swung open, so as to prevent possible damage to the knife 115 and also holds the roll lowered until the cover is fully closed.

A presser, in the form of an upper feed roll 107, is supported by an arm 108 (Figs. 1, 2 and 3) extending forwardly from the rear of the machine. The arm 108 projects from a vertical post 109 bolted to the frame 7, the post being well to the rear of the machine but only some two and a half inches to the right of the knife edge. The arm at its forward end has a vertical bearing 110 (Fig. 5) for a rod 111 which is slidable in the bearing. The rod 111 is pressed down by a strong spring 112 in the bearing which bears against a shoulder 113 on the rod and on a shoulder 114 of a bore in the bearing. The upper end of the rod has threaded on it a hand-nut 115 which engages the top of the bearing 110 and determines the position of the feed roll above the knife. When it is desired to operate upon the edge of a closed opening in a work-piece the feed roll or presser 107 may be raised for the presentation of the work-piece to the machine by turning a horizontal shaft 116 rotatably mounted in the bearing 110 and having on its inner end a crank-pin 117 which enters a horizontal groove in the rod 111. The shaft has on its outer end at the left-hand side of the bearing a handle 118 by which the shaft 116 may be turned. The rod 111 has at its lower end an enlarged portion 119 (Fig. 1) from which a pin 120 projects upwardly into a vertical groove on the bearing to prevent rotation of the rod. The enlarged portion of the rod has formed in its lower face a rearwardly extending guideway in which a stationary presser foot may be adjustably clamped if desired. When a driven presser or upper feed roll is used, as in the illustrated machine, a bracket 121 is clamped in this guideway. The bracket 121 has pivoted to it on a pin 122, a block 123 in which is rotatably mounted a spindle 124 (Fig. 7) having fixed on its forward end the upper feed roll 107. The pin 122 is almost directly above the rear end of the roll 107 so that, when the block 123 is adjusted about the axis of the pin 122, the angle between the lower edge of the roll and the knife is altered without appreciably raising or lowering the rear end of the roll. The block has in it a spring plunger 99 engaging the bracket and holding the end of a horizontal thumb screw 125 mounted in an arm 126 at the front of the block against the bracket 121. By adjusting the screw 125 the roll 107 is adjusted about the pin 122, and upward thrust on the roll is positively taken by the screw. The rear end of the roll spindle 124 is enlarged at 127 and is bored and slotted to receive the ball-shaped end 128 of a rearwardly extending rod 129, which ball end has projecting through it a pin 130 entering the slot, thereby making a universal connection between the rod 129 and spindle 124. The rod 129 has at its rear end

a second ball 131 and pin 132 which enter a bore and slot formed in the forward end of a horizontal shaft 133 rotatably mounted in a bracket 134 on the vertical post 109 of the frame. The shaft at its rear end has fixed to it a spur gear 135 which meshes with a spur gear 136 on the shaft 69 hereinbefore described as carrying the pair of gears 60, 61 of the two-speed mechanism of the lower feed roll. Since the shaft 69 is carried by the swing cover 50 it is necessary to disengage the spur gears 135, 136 when the cover is opened. For this purpose the bracket 134 is slidable vertically by means of a crank shaft 137 and hand-lever 138 carried by the bracket, the shaft having a crank pin 139 entering a slot 140 in the post 109. To ensure that the bracket 134 has been raised and the spur gears thereby disengaged before the swing cover is swung open, the bracket has fixed in it a vertical pin 141 (Fig. 2) which, when the bracket is lowered, enters a hole in the swing cover 50 and locks the cover in closed position.

A grinding wheel 142 (Fig. 7) for the knife is fixed on the lower end of a spindle which is rotatably mounted in a swinging bracket 143, said bracket being rigid with the grinding wheel sleeve 44 (Fig. 4). The grinding wheel 142 is swung away from the knife 1 about the axis of the feed shaft by a spring (not shown) connected to the bracket and to the frame and is drawn towards the knife by a hand-nut 144 (Figs. 1, 2, 3 and 4) at the front of the machine which engages the frame and is threaded on the forward end of a rod pivoted to the bracket. The grinding wheel spindle has at its upper end a bevel gear which meshes with a bevel gear 145 (Fig. 4) fixed on the grinding wheel driving sleeve 146 within the grinding wheel sleeve 44 and surrounding the feed shaft 42. The bevel gears are enclosed in a casing 147 formed on the swinging bracket 143 and sleeve 44. The grinding wheel driving sleeve 146 has slidingly keyed to one end one member 148 of a friction clutch which is movable along the sleeve into and out of engagement with a second member 149 fixed on the feed shaft 42. The member 148 has formed in it a groove 150 which receives a crank pin 151 on a crank shaft 152 rotatably mounted in the frame. The shaft 152 has on its outer end a handle 154 by which it may be rotated to move the friction members out of engagement, and a spring 155 moves the members 148, 149 into clutching engagement when the handle 154 is turned in a direction to permit them so to be moved.

Although the invention has been set forth as embodied in a particular machine, it should be understood that the invention is not limited in the scope of its application to the particular machine which has been

shown and described.

Having thus described our invention, what we claim as new and desire to secure by Letters Patent of the United States is:

5. 1. A machine of the class described having, in combination, a rotatable knife, a sleeve to which the knife is fastened, a bushing in which the sleeve is rotatably mounted, a thrust bearing between the bushing and the sleeve, and means for adjusting the bushing in a path parallel to the axis of rotation of the knife.

10. 2. A machine of the class described having, in combination, a rotatable knife, a sleeve to which the knife is fastened, a driving shaft 15 slideable in and keyed to the sleeve, and a bushing in which the sleeve is rotatably mounted but with respect to which it is held from longitudinal movement, said bushing being slidably mounted for adjustment in the frame of the machine whereby adjustment of the bushing adjusts the knife while the driving connection between the knife and the shaft is maintained.

20. 3. A machine of the class described having, in combination, a cylindrical knife, means for rotating said knife, a feed roll for advancing a piece of work to the knife, a constantly rotating shaft from which the feed roll is rotated, a driving member of a clutch fastened to said shaft, a sleeve rotatable on said shaft, a driven member of the clutch fast to said sleeve, a bevel gear carried by said sleeve, a grinder for the knife, a shaft to which the grinder is fast, a bevel gear on the grinder shaft meshing with the bevel gear on the sleeve, and means for throwing the clutch in or out as may be desired.

25. 4. A machine of the class described having, in combination, a frame having an open end, a cylindrical knife carried by the frame, a cover for closing the open end of the frame, a pivot upon which the frame is hung so that the cover may be swung out when desired, a feed roll carried by the cover, means for rotating the feed roll, a presser roll carried by the frame, and means including a gear carried by the cover and a second gear carried by the frame and meshing with the first-named gear for rotating the presser roll from the feed roll rotating mechanism, one of said gears being movable out of mesh with the other preparatory to swinging open the cover.

30. 5. A machine of the class described having, in combination, a frame having an open end, a cylindrical knife carried by the frame, a cover for closing the open end of the frame, a pivot upon which the cover is hung so that the cover may be swung out when desired, a feed roll carried by the cover, means for rotating the feed roll, a presser roll carried by the frame, means including a gear carried by the cover and a second gear carried by the frame and meshing with the first-named gear 35 for rotating the presser roll from the feed roll

rotating mechanism, one of said gears being movable out of mesh with the other preparatory to swinging open the cover, and means associated with the movable gear for locking the cover in closed position when the gears are meshed and for unlocking the cover when the gears are unmeshed.

70. 6. A machine of the class described having, in combination, a hollow frame, a cylindrical knife the upper portion of which extends above the top of the frame, there being a space between the rear of the knife and the frame, a plate extending substantially across said space, and connections between the knife and the plate such that adjustment of the knife effects adjustment of the plate.

75. 7. A machine of the class described having, in combination, a frame having an open end, a cylindrical knife, a shaft to which the knife is fast, the shaft being rotatably mounted in the frame, a cover for closing the open end of the frame, a pivot about which the cover may be swung when desired, a feed roll, a change speed gearing for the feed roll and a driving member for the change speed gearing all carried by the cover, and a driving shaft carried by the frame, said driving member and driving shaft having interengaging clutch faces.

80. In testimony whereof we have signed our names to this specification.
